United States Patent Office.

THOMAS M. CASH, OF SAN FRANCISCO, CALIFORNIA, ASSIGNOR TO HAGAR & CO., OF NEW YORK CITY.

Design No. 3,811, dated January 11, 1870.

DESIGN FOR PRINTERS' TYPE.

The Schedule referred to in these Letters Patent and making part of the same

To all whom it may concern:

Be it known that I, THOMAS M. CASH, (assignor to Hagar & Co.,) of San Francisco, California, have originated and designed a new Design for Printing-Type, and that the following is a full, clear, and correct description of the same, reference being had to the accompanying drawings, in which several letters of a font are shown, made in accordance with my design, which design is preserved in all other signs, symbols, or other characters made.

What is claimed, as new, is—

The within design for a printing-type, as shown herein.

Witnesses:

A. SIDNEY DOANE,
H. W. HENLEY.

THOS. M. CASH.
